(57) **CLAIM**

The ornamental design for a harness patch, as shown and described.

DESCRIPTION

FIG. 1 is a perspective view of my new design for a harness patch in use, mounted to a harness. The portions of the harness that form no part of the claimed design are shown in broken lines.

FIG. 2 is a top plan view of the harness patch thereof; FIG. 3 is bottom plan view thereof;

FIG. 4 is a rear view thereof;

FIG. 5 is a front view thereof;

FIG. 6 is a left side view thereof;

FIG. 7 is right side view thereof; and

FIG. 8 is a perspective view thereof, in use mounted to a harness worn by an animal. The portions of the harness and the animal that are shown in broken lines form no part of the claimed design.

FIG. 9 is a perspective view of a second embodiment of my new design for a harness patch in use, mounted to a harness. The portions of the harness that form no part of the claimed design are shown in broken lines.

FIG. 10 is a top plan view of the harness patch thereof;

FIG. 11 is bottom plan view thereof;

FIG. 12 is a rear view thereof;

FIG. 13 is a front view thereof;

FIG. 14 is a left side view thereof;

FIG. 15 is right side view thereof; and,

FIG. 16 is a perspective view thereof, in use mounted to a harness worn by an animal.

The portions of the harness and the animal that are shown in broken lines form no part of the claimed design.

The broken lines shown in the drawings illustrate unclaimed portions of the design, or the nature or environment related to the claimed design, and form no part of the claimed design.
